UNITED STATES PATENT OFFICE.

CHRISTOPHER T. FINLAYSON, OF DENVER, COLORADO:

LOCK-CLIP FOR CONNECTING BUCKETS TO TRACTION-ROPES OF AERIAL WIRE-ROPE TRAMWAYS.

SPECIFICATION forming part of Letters Patent No. 738,310, dated September 8, 1903.

Application filed April 27, 1903. Serial No. 154,488. (No model.)

To all whom it may concern:

Be it known that I, CHRISTOPHER T. FINLAYSON, a citizen of the United States of America, residing in the city and county of Denver and State of Colorado, have invented certain new and useful Improvements in Lock-Clips for Connecting Buckets to the Traction-Ropes of Aerial Wire-Rope Tramways; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in rope-clips for connecting trolley-buckets to the traction-rope of aerial wire-rope tramways; and the objects of my invention are, first, to provide a rope-clip that can be used with either the overhead or depending systems of the double-rope type of aerial wire-rope tramways; second, to provide a clip having an automatic lock connection with the trolley of the bucket when applied to the overhead system of wire-rope tramways and to the pendant of the bucket when applied to the depending system of wire-rope tramways; third, to provide means for automatically locking and unlocking the clip to and from the buckets; fourth, to provide a clip that when locked is positively connected and fixed against slipping movement or accidental displacement from its connection with the trolley-bucket in the direction of movement of the traction-rope and bucket and one that while it is so connected to the bucket is at the same time pivotally connected to it in such a manner that it will swing transversely over the trolley of the bucket through a sweep of about a half of a full circle and substantially an equal distance transversely of the run or lay of the rope in a vertical plane when attached to the pendant of the bucket in the depending system. I attain these objects by the mechanism illustrated in the accompanying drawings, in which—

Figure 1 represents a side elevation of my improved lock-clip applied to a trolley of a bucket and as applied to the overhead system of wire-rope tramways. Fig. 2 represents a

plan view of Fig. 1. Fig. 3 represents a section-end elevation of Figs. 1 and 2 on line 3 and 3 3 and also shows an end elevation of the rod-guides I preferably employ to lock and unlock the clip to or from a trolley-bucket. Fig. 4 represents a perspective view of my improved locking-clip secured to a rope. Fig. 5 represents a perspective view of locking and unlocking yoke. Fig. 6 represents an end elevation partially in section on line 6 6 of Fig. 5. Fig. 7 represents a plan view of the clip's locking-bolt holding-socket. Fig. 8 is an end elevation of the locking-bolt's holding-socket shown in Fig. 7. Fig. 9 is a vertical sectional elevation of Fig. 7. Fig. 10 is a side elevation of a wire-rope tramway of the overhead-system type, showing a trolley-bucket operatively mounted on the track or stationary rope and my improved lock-clip operatively connecting the bucket to the traction or running rope and a side elevation of the guide-track device shown in Fig. 3, which I employ at the terminals of the tramway or at any predetermined point in the tram-line to automatically lock and secure the clip to or to unlock and release the clip from a trolley-bucket. Fig. 11 represents a side elevation of my improved lock-clip operatively applied to the depending type of wire-rope tramways, in which case it is connected directly to the pendant of a trolley-bucket and is illustrated mounted in a swiveling frame arranged to swivel or rotatably oscillate in alinement with the run or lay of the traction and track ropes. Fig. 12 represents a sectional view of Fig. 11 on line 12 12 looking in the direction of the arrow A A, showing a sectional elevation of Fig. 11 and an end elevation of the locking and unlocking device shown in side elevation in Fig. 9. Fig. 13 is a side elevation of the lock-clip's locking-bolt holding-socket as shown in the depending system.

Similar figures of reference refer to similar parts throughout the several views.

In all the figures of the drawings except Figs. 11, 12, and 13 I have preferably illustrated my invention operatively connected to the overhead system of aerial wire-rope tramways, by which I mean the system in common use in which the traction or running rope is placed above the stationary or track rope; but in Figs. 11, 12, and 13 I have illustrated

my improved lock-clip operatively connected to the depending system of aerial wire-rope tramways, by which I mean the system in common use in which the traction or running rope is placed below the stationary or track rope. The construction of my improved clip is the same for use with either system. The location and manner of attachment to a trolley-bucket is, however, slightly different, as 10 will be explained fully hereinafter.

Referring to the drawings, the numeral 1 designates the stationary or track rope of an overhead type of a wire-rope tramway, and 2 the traction or running rope. The traction-rope is an endless continuously-running rope which is mounted on sheaves which are supported at the ends of a tramway-line by suitable structures called "terminals," which are designated as "loading" and "dumping" terminals or "upper" and "lower" terminals. There are two stationary or track ropes, only one of which is shown. These are attached to the opposite sides of the terminals to their inner ends and connect to a metal track which 25 extends around the terminal, and thus forms a continuous track. Intermediate of the terminals the traction-rope is supported on sheaves and the stationary ropes on saddles placed at the top of suitable towers. I do not 30 illustrate the terminals or towers, as they do not form a part of my present invention.

The numeral 3 designates a trolley. This trolley consists of a yoke-shaped casing 4, in which I pivotally mount on shafts 5 and 6 sheave-wheels 7 and 8, which are adapted to run on the track-rope. Between the sides of the casing and between the wheels I secure a spreader-block 9 by the rivets 10. Through the lower part of the casing and the spreader-block I form an aperture 12, in which I rotatably mount a shaft 13, in the circumference of which I form a semicircular groove 14. A screw 15 is threaded into the bottom of the spreader-block and its point extends into the groove 14 and secures the shaft to the trolley. If preferred, the groove may be dispensed with and the adjacent end may be upset, or, if desired, both may be used. The opposite end of the shaft extends beyond the trolley-casing and is of smaller diameter and extends through the top of a casting 16, that forms the apex of the pendant 17 of the bucket 18. The end of the shaft is upset to tightly secure the pendant to the shaft between its 55 upset end and the shoulder of the shaft. The pendant comprises two metal bars that are secured at one of their ends to the apex-casting and diverge outward and extend downward and are pivotally connected to the ends 60 of the buckets 18 by the trunnion-pins 19. The spreader-block extends through an opening in the top of the casing above it for a short distance and at its top end a cross-bar projects across its vertical portion and extends 65 a short distance on either side of it and centrally along the longitudinal length of the trolley and forms the locking-socket. This

socket comprises two short tubular lugs or tubes 20 and 21, the outside ends 29^A and 20^B of which are outwardly flared. These tubular lugs are separated a short distance apart by a downwardly-sloping recess 22, which extends from one side of the top of the spreader-block downwardly between the tubular lugs to the opposite side of the spreader-block. 70 An axial aperture 21^A extends through both lugs, and a portion of this aperture extends into and across the bottom of the inclined recess, thus forming a straight continuous aperture through the clip-locking socket. A 80 guide-recess 23 is formed in the top of the casing from end to end in alignment with the aperture through the socket, and the ends of the casing are curved downward to guide the clip easily into the socket. Through the sides 85 of the shells of the tubular lugs I form slots 24 and 24^A, which extend horizontally into their axial apertures on the recess side of the socket, and at the side of the tube, centrally of the recess 22 and adjacent to the bucket's 90 pendant, a pair of ears 25 are formed at a short distance apart, to which is pivotally secured, by a pin 25^A, one end of an actuating-lever 26, which is pivoted to swing vertically through an arc of a circle at right angles to 95 the axis of the aperture in the socket. The function of this lever will be fully described hereinafter. Round bearings 27 and 28 are formed on the socket on each side of the recess 22. Upon the round bearings of the 100 socket I pivotally mount two rings 29 and 30, which form the terminal ends of an oscillating yoke 31, the cross-bar portion of which is slidably connected to the actuating-lever 26 adjacent to its end that is pivoted to the ears 105 25 of the socket. The rings each contain a slot 32 and 33, which are arranged to stand substantially opposite one another, but enough out of axial alignment with each other, so that when the body of the clip passes 110 through one slot it will strike the side of the opposite ring, and the yoke and opposite ring would have to be moved in line with the body of the clip to allow it to pass through the slot of the opposite ring. The slot 32 in the ring 115 29 is a tapering slot, its lower side wall being formed with a downward-diverging incline from the inside of the ring toward its outside end. The slot in the ring 30 is a straight slot arranged to be easily entered by the body of 120 the clip.

The yoke 31 is preferably constructed in the following manner: The rings are preferably made in two halves, each half being arranged to form a part of the ring and form 125 the slots 32 and 33. One-half of each ring is formed with stem portions 36 and 37 opposite their slot-forming ends, on the end of which there is formed short lugs 38 and 39, which project at right angles to the stem of the 130 rings. The ends of these lugs are provided with an enlarged collar portion 40 and 41. An aperture is formed through these lugs and the ends of the stem of the rings, in which ex-

tends a pin 42. The center 42^A of this pin is of larger diameter than its ends that project through the lugs and the enlarged central portion shoulder against the ends of the lugs, 5 while the ends of the pin are riveted to rigidly secure the ends of the pin and the lugs together against the enlarged shouldered portion, thus uniting the stems of the half-rings into a yoke. The other half of each ring is 10 provided with a stem portion which overlaps and is secured to the stem's portion of the opposite half of each ring by rivets 43. The parts of the yoke are thus easily and quickly assembled together and connected to the bearings 15 of the socket to the lever 26.

The actuating-lever 26 is provided with a right-angled aperture 44, one part of which is formed parallel with the lever. In this right-angled aperture the center 42^A of the 20 pin 42 of the cross-bar of the yoke between its collars is slidably mounted, so that as the actuating-lever 26 is swung vertically on its pivotal pin 25^A the rings of the yoke will rotate on the bearings of the socket, and the 25 slots in the rings can be moved to register alternately with the slots in the end tubes of the socket by predetermined movements of the lever 26. The free end of the lever extends a short distance beyond the right-angled slot 44, and at its ends a knob or head 45 is formed.

The rope-clip of my improved rope and bucket lock-clip comprises a flat thin blade 45^A, which I term the "body" of the clip. This 30 blade is provided at the corners of one of its ends with two projecting plate portions 46 and 47, which are separated a short distance apart by a recess. These projecting portions are adapted to form bands to clamp the clip 35 to the rope. The surface of these band portions that lays against the rope is preferably provided with spiral flutes arranged to register with the lay of the strands of the rope. These bands are heated and folded tightly 40 around the rope and their ends lap over onto the body of the clip and are rigidly riveted there. The opposite end of the body of the clip is provided with a cartridge-shaped end 48, which I term the "bolt" of the lock-clip. 45 This bolt extends across and beyond the end of the body of the clip and at right angles to it and parallel to the run of the rope, thus forming a T-shaped end of the free end of the clip. This bolt 48 is preferably round 50 and the ends taper to a point in order that it may very easily enter the outwardly-flared ends of the end tubes of the socket. The actuating-lever 26 may be operated to automatically operate the yoke to lock and unlock 55 the bolt of the clip in the clip's socket by variously-arranged levers positioned at the terminals and at points where it is desired in the length of a tram-line to connect and release the buckets and rope, or what is 60 the same, the clip of the rope and the socket of the trolley. I preferably employ, however, a pair of rods or rails 49 and 50. These

rods may be supported at the side of the rope in any desired manner in the running path of the actuating-lever. These rods are arranged parallel to each other and are positioned at a sufficient distance apart to form a slot a trifle wider than the thickness of the end of the actuating-lever adjacent to the knob or ball at its end. The actuating-lever 70 in order to operate the yoke to lock and unlock the bolt of the clip when the clip enters and leaves the socket must travel in a circle in a vertical direction around its pivotal support, and the guide-rails which operate it are 75 curved to form an arc of the same radius as the actuating-lever makes close to the ball at its end, as shown in Fig. 3, and in order to move the lever up and down to operate the lock and unlock the bolt when it enters the 80 socket, I arrange the rods in the following manner: The lower rod 49 is positioned with one of its terminal ends below the lowest point, the ball at the end of the actuating-lever 26 moves to on the actuating-lever's 85 downward stroke, which is preferably at about a sixty-degree angle downwardly from its pivotal center, at which inclination it just clears the apex of the pendant of the bucket. The actuating-lever is a gravity-locking lever, as 90 its weight keeps it hanging normally downward, and as it moves downward it turns the yoke on the bearings of the socket, so that the slots in it, through which the body of the clip passes, also stand at an upward vertical angle, 95 preferably of about sixty degrees; but as the cross-bar of the yoke is moved down with the lever its lever-connecting pin slides down in the part 53 of the right-angled slot until it reaches the part 54 of this right-angled slot, 100 into which it moves as the lever continues moving down until it reaches the end of the part 54 of the slot, against which it abuts and stops and locks the lever against further downward movement, and at the same time 105 the yoke itself is locked against turning on the bearings of the socket except an upward movement be given to the ball end of the actuating-lever. The trolley-bucket is moved manually after it is either loaded or dumped 110 to a point where the clip can pick it up, as will be explained hereinafter. Consequently assuming that the clip is locked in the socket and the bucket is attached to the traction-rope, the guide-rails must be arranged to 115 catch the actuating-lever close to its ball end and raise it up high enough to turn the slots in the rings of the yoke, first, to free the bucket from the clip by turning the yoke so that the ring 30 will register in alinement 120 with the slot 24^A in the end tube 21 of the socket, which will allow the body of the clip to pass through the slots 24^A and 33 of the socket and yoke, respectively, and allow the bolt of the clip to pass out of the socket; sec- 125 ond, to then move the actuating-lever down to a horizontal position, which will turn the yoke's rings on the bearings of the socket and bring the tapering slot 32 of the ring of the 130

yoke in alinement with the slot 24 in the end tube 20 of the socket to allow the bolt and body of the clip to pass into the socket and again connect a bucket to the continuously-
 5 running traction - rope, and, third, to then move the actuating-lever down to the limit of its downward stroke to turn the yoke-rings on the socket to turn both of the rings of the yoke, so that their slots will both be moved.
 10 far enough away from the slots in the socket to make accidental detachment of the clip from the socket and of the bucket from the rope impossible, as shown in Fig. 3. Consequently the terminal end of the rod 49, which
 15 is positioned to receive the moving clips, is placed below the limit of the downward movement of the actuating-lever and inclines upward at a suitable angle for the actuating-lever to slide up when it strikes it. (See Fig.
 20.) This upwardly-inclined portion of the rod 49 is of sufficient length to raise the actuating-lever high enough to bring the slot of the yoke-ring 30 to register with the slot 24^A in the end tube 21 of the socket, which
 25 will permit the bolt and the body of the clip to pass out of the socket. The rod 49 is then bent and extends in a straight horizontal plane portion 55 for a distance sufficient to hold the actuating-lever up, and consequently
 30 the said slots, in registering alinement until the clip has passed fully out of the socket. The top rod 50 at this end is arranged in a straight horizontal plane to the front end of the rod 49 and at a sufficient distance above
 35 the straight portion 55 of the rod 49 to form a loose slideway-slot 56 between them for the actuating-lever close to the ball at its end, which projects through the slot between the rods and travels along on the opposite sides
 40 of the rods from the trolley buckets and ropes of the tramway. At the end of the horizontal straight portion of the rods they both bend downward at an outward angle and extend at this angle a sufficient distance to carry the
 45 actuating-lever to the central or horizontal position of its movement, in which position the slot 32 of the ring 29 of the yoke is brought to register in alinement with the tapering slot 24 of the tube 20 of the socket, which allows
 50 the bolt and body of the clip to enter the socket. At this point both rods are again bent and extend horizontally a distance sufficient to allow the clip to fully enter the socket, when both rods are again bent and ex-
 55 tend downward at an outward angle a distance sufficient to move the actuating-lever to the end of its downward movement, which turns the slots of the yoke upward away from the slots in the socket and positively locks the clip
 60 to the socket and the bucket to the rope, the rods being arranged parallel to each other from the highest point they raise the actuating-lever to the lowest point they leave it at and at a sufficient space apart to allow the ac-
 65 tuating-lever to slide loosely between them.

The proper position for the clip and traction-rope when passing around the terminal

of a tram-line and also between the terminals when passing over the supporting-sheaves of the towers is in a horizontal plane, as shown 70 in Fig. 3.

In the construction of a tram-line over a rough mountainous country it is often necessary to make curves and to lower or raise the running rope and to even carry it up and 75 over the vertical center of the trolley to the opposite side of the trolley and bucket. The overhead system of wire-rope tramways is, however, the only system in which the traction-rope can be carried up over the trolley 80 of the bucket and from one side of the trolley to its opposite side. This system is very fully illustrated in its various parts in my applications for patents, Serial No. 134,420, filed December 8, 1902, Serial No. 136,726, filed December 26, 1902, Serial No. 139,612, filed January 19, 1903, and Serial No. 144,853, filed February 24, 1903. My bucket and rope clip is especially adapted for use with this overhead system as disclosed in these above- 90 named applications, as the rope and clip can and is free to swing at all times in a transverse vertical plane from considerably below the normally horizontal position of the clip and rope up and over the vertical center of 95 the socket and trolley to its opposite side, and in any position they may assume the rope can be supported by suitable sheaves, as indicated by the dotted lines in Fig. 3.

In Figs. 11, 12, and 13 I illustrate my new 100 lock-clip applied to a tramway system of the depending type. In adapting my invention to the system no changes are necessary in the locking parts of the socket-yoke, actuating-lever, or guide-rods; but some slight additions 105 for supporting and connecting the lock-clip to the pendant are necessary, as in this system the clip is attached to the pendant of the bucket instead of to the trolley, as in the overhead system. Consequently it is necessary 110 to make the socket separate from the spreader-block and to mount it on a suitable supporting-frame that can be attached to the pendant of the bucket. I preferably carry out this feature of my invention in the following manner: I secure to the side of the pendant two cross-bars 57 and 58, which I place at a short 115 distance apart. To these bars I secure by bolts 59 two oppositely-arranged flange-plates 60 and 61, which form the fastening plates of a 120 disk-shaped supporting-ring 62, of which these flanged plates form an integral part. One side of each of these flanged plates is provided with a projecting lip which rests against the same side of both of the cross - bars. I 125 mount rotatably in this fixed ring 62 a swiveling ring 63, the outer edge of the flange of which overlaps the supporting-ring on its side toward the ropes 1 and 2 and the clip of the tramway. This swiveling ring is provided 130 with lugs 64 and 64^A, which are positioned at suitable distances apart around its peripheral ring portion, and a cap-ring 65, which is fitted to register with it and to lap over onto the

fixed ring, is secured by screws 66 to it on the opposite side of the fixed ring. In order to secure the socket to the swivel-ring, I provide it, as shown in Fig. 13, with projecting screw-lugs 67, which are formed on it in positions to register over the rear end of four of the lugs 64^A the cap-ring is secured to. I then secure these lugs 67 to the opposite ends of the lugs 64^A from the cap-ring and on the side of the swiveling ring adjacent to the ropes of the tramway by the screws, which are long enough to pass through the cap and lugs and screw into the lugs of the socket, as shown in dotted lines in Fig. 12. The socket is thus swivelingly mounted in the fixed ring of the pendant. The yoke is mounted on the bearings of the socket and is arranged as in the overhead system; but the actuating-lever is pivotally connected to two ears 68, which project from the rear side of a collar portion 69, that is formed on the center of the socket between the bearings of the yoke's rings. This collar portion does not extend entirely around the center of the socket, but on to a trifle beyond the top and lower portion of the socket, where it terminates to inclined walls that converge to the axial aperture 21^A of the socket, thus leaving a large central opening surrounding the horizontal position of the clip. This central angular space permits the traction-rope and the clip to swing on the clip's bolt in the socket above and below the normal horizontal position of the clip, as indicated by the positions of the clip and rope and its supporting-sheaves in dotted lines in Fig. 12. The swiveling connection of the socket to the fixed ring of the pendant permits the clip and socket to adjust themselves to the vertical inclinations of the ropes relative to the vertical run of the ropes of a tram-line that runs up or down mountainous countries; as the buckets always stand substantially in a vertical plane, while the rope may be positioned either up or down at a very steep inclination.

45 The operation is as follows: The traction-rope is a continuously-running rope, and it is moved on trams built to convey ores and other material down mountainous and hilly countries by the weight of the loaded buckets, and when a tram-line is level or conveys material up an incline it is moved by power. The clips are secured to the traction-rope at suitable distances apart, and the sockets are secured to the trolleys or to the pendants of the buckets, as the case may be. A number of buckets are employed, and an equal number of clips are secured at substantially equal distances apart in the length of the endless continuously-running traction-rope. The buckets enter the unlocking and locking guides in the direction of the arrow 70. (See Fig. 10.) Upon coming in contact with the lower rod the actuating-lever is raised to the top rod and to the horizontal slot between. 55 This upward movement of the actuating-lever turns the rings of the yoke to register with the slots in the socket, allowing the

bolt of the clip and its body portion to be moved out of the socket, as the bucket 18 will slow down and stop, while the traction-rope and the clip continue on without in the least slowing up, and the released bucket may be dumped or loaded, as required, and then be moved into the connecting position C C by any suitable means to be again attached to a clip of the traction-rope. A bucket is always moved and kept standing at the clip-connecting station before the bucket behind it is released, and as the actuating-lever comes down to the bottom of the incline B B of the actuating-lever's actuating-rods and the slot 33, that registered with the slot 24^A and allowed the clip to pass out of the socket, turns upward again the slot 24^A in the socket is closed by the solid portion of the ring 30, thus closing the passage out of the socket; but this downward movement of the actuating-lever at the same time brings the slot 32 of the ring 29 in alignment with the slot 24 of the socket and the clip as the actuating-lever passes along the horizontal portion of the slot C C in the actuating-lever's operating-rods, passes through the slots 24 and 32 into the socket and strikes against the side of the ring 30 of the yoke, and thus picks up and moves the bucket along with it, and when the actuating-lever runs down the incline slot E E of the actuating-lever's operating-rods the slot 32 of the ring 29 of the yoke is turned up above the slot in the socket, which is covered by a solid portion of the ring, and the socket and bucket are locked to the clip and traction-rope.

Having described my invention, what I claim as new, and desire to secure by Letters Patent, is—

1. In a clip for alternately connecting and releasing buckets to and from the traction-rope of wire-rope tramways, the combination with the rope and the trolley of the clip-plate secured to said rope at one end, an enlarged head end on the free end of said clip, the socket secured to said bucket and adapted to receive the enlarged end of said clip, the yoke rotatably mounted on said socket and means for operating said yoke to lock and unlock said clip from said socket, substantially as described.

2. In a clip for alternately connecting and releasing buckets to and from the traction-rope of wire-rope tramways, the combination of a plate-clip secured at one end to said traction-rope, a cross or T-shaped bolt end at the free end of said clip, a socket provided with an axial recess secured to a part of said bucket's support, a central recess in said socket into the axial aperture thereof and slots in the end portions of said socket adapted to allow said bolt and body of said clip to pass through said socket and means for locking said clip in the center recess of said socket, substantially as described.

3. In a rope-and-trolley-bucket-connecting clip, the combination with the trolley, of a

- spreader-block secured thereto provided with an upwardly-extending portion having a right-angled cross portion comprising a hollow socket or tube provided with flaring ends, 5 a downwardly-sloping recess in the center of said tube horizontally-arranged slots in the ends of said socket, round bearing portions on said socket at each side of said central portion, rings connected rigidly together by a yoke-shaped bar rotatably mounted on said bearings, a slot in each ring arranged to alternately register with the slots in said socket but arranged out of alinement with each other so that one of the rings will be in position to 10 cover the slot in one end of said socket, when the slot in the opposite ring registers with the slot in the opposite end of said socket, means including a lever for operating said rings to open and close said slots and a clip secured 15 at one end to a rope and having its opposite end arranged to enter said socket and to be locked to and released from said socket by a partial rotative movement of said rings, substantially as described.
- 20 4. In a traction-rope and trolley-bucket lock-clip, the combination with the rope of a trolley provided with a socket having slots through its sides, a clip attached at one end to said rope and having its free end arranged 25 to move into and through said socket, means including slotted rings mounted on said socket for automatically securing said clip to, and releasing it from said socket and trolley, substantially as described.
- 30 5. In a rope-and-trolley-bucket-connecting clip, the combination with the trolley provided with two tubes at its top spaced at a short distance apart, a downwardly-sloping recess between said tubes and having said 35 tubes provided with horizontally-arranged slots in alinement with each other adapted to form a passage through said tubes, rings rotatably mounted on said tubes and provided with slots out of alinement with each other 40 but arranged and adapted to be alternately moved over first one slot-passage of one tube and then over the other slot-passage of the opposite tube, means including a lever for moving said rings to open and close said slot- 45 passages through said rings, and a clip secured at one end to said rope, and having its opposite end arranged to enter and pass through said tubes and their slot-passages and arranged and adapted to be unlocked by 50 a rotative movement of said rings on said tubes in one direction and free to move out of said tubes and to enter said tubes and be locked and held centrally between them by a rotative movement of said rings in opposite 55 direction, substantially as described.
- 60 6. In a rope-and-trolley-bucket-connecting clip, the combination with a bucket-trolley comprising a casing, sheave-wheels mounted in said casing, a spreader-block secured to 65 said casing between said sheave-wheels, a pendant pivotally secured at one end to one side of said trolley, a bucket pivotally at- 70 tached to the opposite end of said pendant, a downwardly-inclined recess in the top of said spreader-block and casing extending 75 from the top of the pendant side of said trolley downward to its opposite side, a tubular lug on the top of said spreader-block on each side of said recess, an axial bore extending through said tubular lugs, a part of which passes through the bottom of said recess, a horizontal slot extending through the shell of each tubular lug into its axial bore from the recess side of said spreader-block and in longitudinal alinement with each other, and 80 a round bearing portion on the inside edge of each tubular lug, of a pair of rings connected together by a yoke-shaped arm rotatably mounted on said bearing portions, a slot through the shell of each ring arranged out 85 of alinement with each other but arranged and adapted to alternately register with the slots in said tubular lugs by rotative movement of said rings, a lever pivotally connected at one end to said spreader between 90 said tubular lugs, an angular slot in said lever intermediate of its ends slidably connected to the yoke-shaped connecting-arm, a clip secured at one end to said rope, a round stem member at its opposite end adapted to 95 fit loosely into said tubular lugs and to pivotally rest in them when in operative relation to them, a thin plate body portion adjacent to said stem member adapted to fit loosely in said slots in said rings and tubular lugs and 100 swing vertically between them on its pivotal stem portion, and rods supported in the path of said lever and trolley-bucket arranged and adapted to raise and lower said lever to rotate said rings to unlock and to lock said clip 105 in the tubular lugs of said trolley, substantially as described.
7. In a bucket-and-traction-rope-connecting lock-clip, the combination with the trolley, of the socket comprising the tubular lugs, 110 the downwardly-inclined recess between said lugs, the slots in said lugs and the locking and unlocking rings rotatably mounted on said lugs, substantially as described.
8. In a bucket-and-traction-rope-connecting lock-clip, the combination with the trolley, the pendant pivotally secured thereto and the socket comprising the slotted tubes having a downwardly-inclined recess between 115 containing a semicircular recess in alinement with the aperture through said tubes, and the yoked rings rotatably mounted on said tubes, and provided with slots arranged out of alinement and adapted to register in alternate order with the slots of the tubes of 120 said socket, of a lever pivotally secured at one end to said trolley, a right-angled slot in said lever intermediate of its ends in which the cross-bar of said yoke is slidably secured, a clip secured at one end to said rope and 125 having a free end arranged to enter said socket's tubes, and pass through the slots of said tubes and yoke-rings, and means for operating said lever to lock and to release said 130

clip to and from said socket, substantially as described.

9. In a bucket-and-traction-rope-connecting clip, a clip comprising a flat, thin blade 5 provided with projecting bands or ribbon at one end arranged and adapted to be folded around said rope and to rigidly secure said clip to said rope, an enlarged round stem having pointed ends extending across the opposite end of said blade and beyond it on each side and arranged parallel with the width of the blades, substantially as described.

10. In a traction-rope-and-trolley-bucket-connecting clip, a socket secured to said trolley-bucket comprising slotted tubes spaced at a short distance apart and having their apertures and slots in axial alinement with each other, a lever pivotally secured at one end to

15 said socket laterally at one side of the axial centers of said tubes, two rings rigidly connected together by a yoke-shaped arm, each one of said rings being loosely mounted on one of said tubes, a slot in said lever intermediate of its ends and substantially parallel with its length, 20 a lateral extension to said slot, a cross-bar portion to said yoke slidably connected to said slot and adapted to move into said lateral extension of said slot at the limit of the downward movement of said lever whereby said 25 lever and said yoke, owing to their differential axial centers are locked against further downward movement and said yoke is locked against independent or accidental rotative movement on said tubes, substantially as described.

30 11. In a traction-rope-and-trolley-bucket-connecting clip, the combination of the trolley-easing having a longitudinal groove centrally in its top, the socket-rings secured to said trolley-

35 lever in alinement with said groove, a clip secured at one end to said rope and having its opposite end provided with a pointed stem member arranged across its free end and arranged and adapted as it travels with said

40 rope to enter the groove in the top of said trolley-easing and be guided into said socket-tubes, and means including an actuating-lever for locking said clip to, and for unlocking said clip from, said socket-tubes of said 45 trolley, substantially as described.

50 12. In a traction-rope-and-trolley-bucket-connecting clip, the combination with the stationary or track rope, of the trolley's sheave-wheels mounted thereon, a casing in which

55 said sheave-wheels are operatively supported, a curved groove centrally in the top of said casing along its length, a spreader-block secured to said casing between said sheave-wheels having tubes at its top, spaced at a

60 short distance apart provided with outwardly-flaring entrance ends and arranged in alinement with said groove in the top of said casing, horizontal slots in said tubes in alinement with each other, yoke-connected rings

65 rotatably mounted on said tubes provided with slots through their shells arranged out of alinement with each other but adapted to

register alternately with the slots in said tubes, a clip secured at one end to said traction-rope and having a T-shaped free end 70 arranged and adapted to pass into and through said tubes and rings, a lever pivotally connected to said spreader-block between said tubes having a ball or knob head at its free ends, guide-rails arranged in the path of said lever and spaced at a suitable distance apart to receive, guide, and raise and lower said lever whereby said lever is raised and lowered to unlock the free end of said clip and to lock it to said trolley, substantially as described.

75 13. In a traction-rope-and-trolley-bucket-connecting clip, the combination of the trolley; the socket connected thereto; the yoked locking-rings mounted thereon, and the actuating-lever arranged and adapted to move vertically in an arc of a circle with a pair of guide-rods arranged in the traveling path of said trolley and yoked ring's clip locking and unlocking actuating-lever and arranged and adapted at a short distance apart to form a guide-slot between them through which the free end of said actuating-lever is adapted to move, and arranged first with an upward incline portion adapted to raise said actuating-lever to move said yoked rings to unlock said clip from said trolley's clip-receiving socket and then formed with a horizontal straight slot portion adapted to hold said lever up in an unlocked position while the bucket slows 90 down to a stop, and the clip moves out of said socket and then bent downward to a position to permit a clip to enter said socket and extended in a horizontal position for a sufficient distance to allow said clip to enter 95 said socket and pick up said bucket, and then bent downward to move said lever down to lock said clip to the socket and to said trolley-bucket and having said rods curved to register with the radius of the free end of 100 said lever, substantially as described.

105 14. In a traction-rope-and-trolley-bucket-connecting clip, the combination with the clip and the pendant of the bucket, of cross-bars secured to said pendant; a ring fixed to 110 said cross-bars; a ring revolvably mounted in said fixed ring and means for securing the socket of the clip to said revolvable ring, substantially as described.

115 15. In a traction-rope-and-bucket-connecting clip, the combination with the pendant of a fixed ring secured to said pendant; a ring rotatably mounted in said fixed ring, a clip-locking socket secured to said rotatable ring comprising two tubes spaced at a short distance apart and provided with outwardly-flared tubular ends, horizontal slots in said tubes, a collar portion on said socket centrally between said tubes and having the apertures of both tubes extending axially 120 through said collar, an angular space in one side of said collar extending into its axial bore, horizontal slots through said end tubes in alinement with one another through said

125 130

angular space in said collar, a clip secured at one end to said traction-rope and having its opposite end formed into a T-shaped locking-bolt, rings rotatably mounted on said tubes, a lever pivotally secured to said collar portion and projecting through said rotating ring of said pendant and extending through said ring, a pivotal sliding connection between said yoked rings and said lever, horizontal slots in said yoked rings arranged to alternately lock and unlock said clip to said socket, and suitable guide-rods arranged to operate said lever, substantially as described.

16. In a traction-rope-and-trolley-bucket-connecting clip, the combination with the pendant of the fixed ring secured thereto, the ring rotatably mounted in said fixed ring the socket secured to said rotatable ring; a clip secured at one end to said traction-rope, a stem-shaped bolt member arranged to enter said socket at its free end and means including the yoked rings rotatably mounted on said socket for locking and unlocking the clip to said socket, substantially as described.

17. In a traction-rope-and-trolley-bucket-connecting clip, the combination with the clip comprising a thin plate provided with a bolt member at its free end, and secured at its opposite end to said traction-rope, of a socket comprising a tube having outwardly flaring ends, a horizontal slot extending through said socket, an inclined recess in said socket intermediate of the ends of said socket, a rocking member mounted on said socket provided with slots arranged out of alignment with each other and arranged to alternately register with said slots in said socket, means for securing said socket to said trolley-bucket; and means for operating said rocking member to release and lock said clip from and to said socket, substantially as described.

In testimony whereof I affix my signature in presence of two witnesses.

CHRISTOPHER T. FINLAYSON.
